AIR VENTILATING PANEL STRUCTURE AND AN
AIR CONTROL VALVE THEREFORHarry W. Carlson, Palatine, Ill., assignor to Simpson
Timber Company, a corporation of Washington

Filed May 29, 1967, Ser. No. 642,019

4 Claims. (Cl. 98—41)

ABSTRACT OF THE DISCLOSURE

An air ventilating ceiling can be assembled from panels containing discontinuous air control valves ported air passages therethrough. The control valves fit into their respective air passages, occupy little space on the plenum chamber side of the panel, and are individually adjustable from below so as to provide precise air circulation through the room.

In brief, this invention comprises a plenum chamber ventilating panel, for example an acoustical tile employed in a false ceiling where a ventilating air plenum chamber is contained between the false ceiling and the actual ceiling, and further comprises a valve mechanism for use with the ventilating panel. This invention will find its greatest application in ventilating-type ceiling and therefore an acoustical-type ventilating panel would usually be employed.

In the drawing:

FIG. 1 is a plan view of a portion of the room side of an acoustical tiled ceiling depicting an acoustical tile with a pair of valved air passages therethrough;

FIG. 2 is a cross section taken along the line 2—2 of FIG. 1 depicting an exemplary valved air passage through the acoustical tile;

FIG. 3 is a plan view of the air plenum chamber side of the valve depicted in FIGS. 1 and 2; and

FIG. 4 is a perspective view of the FIG. 3 valve.

Referring to the Figs., acoustical ceiling tile panels 10 are provided with a plurality of air passages 15 extending transversely therethrough, preferably at least two as shown in FIG. 10, with an air control valve 12 mounted in each air passage to control air flow therethrough. The air passages may be of any desired configuration such as the elongated configuration with semi-circular ends shown in the Figs. It is preferred that the air passages be standardized to permit standardization of control valve structure.

Each control valve comprises a sleeve member insert 14 and a valve element comprising an actuating member or shaft 16 and a slotted cover plate 18. The sleeve member is fitted into the air passage from the plenum chamber side of the tile 10. The sleeve member has the same general outer wall configuration as the inner wall defining the air passage 15 and is only slightly smaller such that the sleeve member is frictionally bound in the air passage when fitted therein. The depth of the sleeve member is preferably less than the depth of the air passage so as to be relatively unnoticeable when viewed from below. The sleeve member has a centrally-positioned web 14a that divides the interior of the sleeve member into two parallel air channels which permit air flow through the passage 15 when the sleeve member is inserted therein. The web 14a is provided with a longitudinal bore that loosely receives the shank of actuating shaft 16.

The shaft 16 is provided with a slotted head and is attached at its opposite end to the thin-walled circular cover plate 18. The slotted head bears against the lower edge of the web 14a to maintain the circular cover plate in close proximity to plenum chamber side of the panel 10. The circular cover is provided with rectangular slots

2

20 and 22, so positioned that they can be rotated into or out of registry with air channels through the sleeve member by inserting a screw driver or the like into the slotted head of the shaft 16 and turning the shaft. These 5 slots are preferably slightly larger than the air channels through the sleeve member.

The air passages 15 are preferably provided in sufficient number to constitute about 2 percent of the paneled surface so as to permit a suitable degree of air circulation.

10 The sleeve member 14 is thin-walled so as to provide maximum-sized air channels communicating with the respective air passage 15.

If desired the components of the valve mechanism could be fabricated of plastic materials and adapted to be 15 snapped together when assembled.

It is believed that the invention will have been clearly understood from the foregoing detailed description of my now-preferred illustrated embodiment. Changes in the details of construction may be resorted to without departing from the spirit of the invention and it is accordingly my intention that no limitations be implied and that the hereto annexed claims be given the broadest interpretation to which the employed language fairly admits.

The embodiments of the invention in which an exclusive 25 property or privilege is claimed are defined as follows:

1. A ceiling ventilating panel which comprises a panel having upper and lower surfaces and an elongated air passage extending therethrough; and an air control valve comprising an elongated sleeve member inserted into said 30 air passage and a thin flat slotted cover plate overlaying the panel's upper surface with a transverse width greater than the elongated length of said air passage and an actuating shaft journal mounting said cover plate to said sleeve member and extending through said sleeve member such that said cover plate can be rotated from below to bring the slots therein into and out of overlaying registry with said air channel, said sleeve member having an outer surface configuration substantially conforming to the inner wall surface defining said air passage such that the sleeve 35 member is frictionally bound in said air passage when inserted therein, and said sleeve member having an air channel extending therethrough to permit air flow through said air passage.

2. A ceiling ventilating panel according to claim 9 45 wherein said sleeve member has a depth less than the width of said panel such that when inserted into said air passage with the sleeve upper end flush with the panel upper surface the panel member lower end will be confined within said air passage above the panel lower surface.

3. A ceiling ventilating panel according to claim 9 wherein said sleeve member has two parallel and discreet air channels therethrough divided by a web; and wherein said actuating shaft extends through the sleeve member 55 web.

4. A ceiling ventilating panel which comprises a panel having upper and lower surfaces and an elongated air passage extending therethrough; and an air control valve comprising an elongated sleeve member inserted into 60 said air passage and a thin flat slotted cover plate overlaying the panel upper surface with a transverse width greater than the elongated length of said air passage and an actuating shaft journal mounting said cover plate to said sleeve member and extending through said sleeve member, said sleeve member having an outer wall surface configuration substantially conforming to the inner wall surface defining said air passage such that said sleeve member is frictionally bound in said air passage when inserted therein, said sleeve member having a depth 65 less than the width of said panel such that when inserted 70

into said air passage with the sleeve upper end flush with the panel upper surface the sleeve member lower end will be confined within said air passage above the panel lower surface, and said sleeve member having two parallel and discreet air channels therethrough divided by a web to permit air flow through said air passage, and said actuating shaft extending through the sleeve member web with the actuating shaft lower end terminating within said air passage such that said cover plate can be rotated to bring the slots therein into and out of over-laying registry with said air channels upon insertion of an actuating tube into said air passage from below.
